(57) **CLAIM**

The ornamental design for a sand vehicle, as shown and described.

DESCRIPTION

FIG. 1 is a perspective view of a sand vehicle showing my design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

The fragmented cross-hatching shown on the leg rest, seat and backrest is understood to represent fabric which would be continuous throughout the implied areas.

1 Claim, 7 Drawing Sheets
